United States Patent

Des. 240,520

Patented July 13, 1976

240,520

SILO DOME

Marion E. Hutchison, 1241 Ackerman St., Waterloo,
Iowa 50701; Vernon O. Thomas, R.R. 2, Charles
City, Iowa 50616; and William D. Shafaz, 405 W.
Plum, West Union, Iowa 52175

Filed Feb. 25, 1974, Ser. No. 445,283

Term of patent 14 years

Int. Cl. D25—02

U.S. CL. D25—56

FIG. 1

FIG. 2

FIG. 3

FIG. 4

FIG. 5

FIG. 6

FIG. 1 is a top plan view of the silo dome showing our new design;

FIG. 2 is a bottom plan view of FIG. 1;

FIG. 3 is a side elevational view of the left side of FIG. 1;

FIG. 4 is a side elevational view of the right side of FIG. 1;

FIG. 5 is a sectional view taken along the line 5—5 of FIG. 1; and

FIG. 6 is an enlarged sectional view taken along the line 6—6 of FIG. 1.

We claim:

The ornamental design for a silo dome, substantially as shown and described.
